UNITED STATES PATENT OFFICE.

FRANCIS J. McLOUGHLIN, OF BROOKLYN, NEW YORK.

DOORCHECK.

Application filed March 8, 1922. Serial No. 541,929.

To all whom it may concern:

Be it known that I, FRANCIS J. McLOUGHLIN, a citizen of the United States, residing in Brooklyn, county of Kings, State 5 of New York, have invented a certain Improvement in Doorchecks, of which the following is a specification.

The present improvement relates to a form of door check for self-closing doors 10 embodying the application of a principle novel in this art. The principal advantages of the invention are found in its cheapness, simplicity, and fewness of parts and in the fact that it is not liable to get 15 out of order.

In its ultimate analysis the apparatus consists of two cooperating members fastened respectively to the door itself and to the edge of the door opening, one of said members being adapted to cause revolution of the other when the door closes while the two move idly past each other on opening the door. There is no air or fluid pressure involved, the resistance to closure of 25 the door resulting from that which is familiarly incident to the revolution of a screw by pressure upon its thread.

The basic principle of the invention is capable of embodiment in a great variety 30 of forms some of which are illustrated in the accompanying drawings wherein Figure 1 is a plan view of one form as seen from above the transom near the hinge, Figure 2 is a view of the same in elevation, 35 Figure 3 is a plan view of a modification, Figure 4 is a perspective view of a portion of the form shown in Figure 3, Figure 5 is a view in elevation of another form, Figure 6 is a horizontal sectional view on the 40 line 6—6 of Figure 5, Figure 7 is a view partly in section and partly broken away of still another form, and Figure 8 is a perspective view of a part of the form shown in Figure 7.

45 In the form shown in Figures 1 and 2, the swinging door 10 is carried on the usual hinges 11, and closes under the top bar 12 of the door frame, which is shown as the bottom bar of the transom.

50 Under this bar 12 there is fastened a plate 13, preferably inset so as not to project below the bar. This plate is furnished with inclined ratchet teeth 14 set on the arc of a circle. Upon one face of the door 10, 55 a stout pin 15 carries a swinging frame 16, at the upper end of which is revolvably

mounted a wheel 17 carrying a spiral ridge 18 whose pitch corresponds to the distance between successive teeth 14. This ridge has a beveled edge, as plainly shown in Figure 60 1. The frame 16 is adapted always to tend toward the toothed plate 13, either by gravity or by the use of a spring, for instance as shown at 19. This holds the ridge 18 in contact with the plate 13. 65

When the door is opened, the beveled edge of the ridge moves idly over the teeth 14, like an ordinary pawl, but when the door is closed, the ridge engages these teeth as shown in Figure 1, and the wheel 17 is 70 revolved rapidly by the pressure of the teeth 14, offering the resistance usual in such cases.

In Figures 3 and 4 is shown a form of the invention in which the toothed sector 13 75 is replaced by a straight bar 20, provided with inclined teeth on its under edge and carried by a universal joint 21 on the top of the door. Upon the door is carried a swivelled frame 22 having slotted guides 23 through which the bar 20 passes. Between these guides is revolvably mounted the wheel 17 with the ridge 18, as described for Figures 1 and 2. In this form it is the bar 20 that yields when the door opens, 80 but holds its engagement with the ridge 18 when the door closes. The resistance to revolution of the wheel 17 checks the door in this as in the first described form. 85

In the form shown in Figures 5 and 6 one 90 member of the hinge 24 carries a toothed ratchet wheel 25, and upon the other hinge member 26 there are brackets 27 upon which a frame 28 is pivoted at 29. This frame carries a revoluble wheel 17 with the ridge 95 18 as before, and a spring 30, bearing on the back of the frame 28, keeps the wheel in engagement with the ratchet. The mode of operation is similar to that already described. 100

Figures 7 and 8 show a form wherein the revoluble member is carried by the door frame. This member is the long spiral wire 31, mounted upon a universal joint 32, of the ball and socket type, on the door frame. Upon the door 10 is mounted a socket 33 carrying a pivoted fork 34. Between the guides 34 rides a vertically movable plate 35, having a depending tooth 36. This is shaped substantially as shown, so that it will ride 105 idly over the screw wire 31 when the door is opened, but will engage with the wire so as

to cause it to revolve when the door closes. It will be noted that there is a straight portion of the wire 31 for a short interval near the door, and by reason of this the tooth 36 5 will be liberated a short time before the door actually closes. This insures the free action of the closing spring to finally close the door.

As shown in Figure 7, the pitch of the screw may be steepened toward its base, so 10 to as to offer an increased resistance at the last, thus insuring a soft and noiseless closing of the door.

The invention may be embodied in many 15 different forms without departing from its principle and I do not limit myself to the details shown and described.

What I claim is—

1. A door check comprising two cooperating members mounted respectively on the 20 door and its frame, one of said members being revoluble by pressure of the other in one direction only and one of said members being adapted to ride idly over the other in the other direction only.

2. Apparatus as in claim 1 wherein one of 25 the members has a tooth so inclined as to permit the other member to yield when the door is opened, said tooth being adapted to

cause revolution of the other member by a sliding thrust when the door is closed. 30

3. Apparatus as in claim 1 wherein one member is mounted on a universal joint on the door frame and passes between guides carried by the door.

4. Apparatus as in claim 1 wherein one 35 member is a wire helix mounted on the door frame on a universal joint.

5. Apparatus as in claim 1 wherein one member is a wire helix mounted on the door frame on a universal joint and wherein the 40 pitch of said helix is made steeper nearer the door frame than further out.

6. Apparatus as in claim 1 wherein one member is a wire helix mounted on a door frame on a universal joint and wherein the 45 coils of the helix are arranged at such a distance from the door frame that the tooth in the member carried by the door passes all the coils of the helix and ceases to engage them before the door is fully closed, thus removing the resistance and allowing the door to finish its closing motion freely and quickly to insure a tight closing.

In testimony whereof I have hereto set my hand on this 3rd day of March 1922.

FRANCIS J. McLOUGHLIN.
